FABRIC CUTTING DEVICE

Nathan Ross, Los Angeles, Calif.

Application December 9, 1932, Serial No. 646,456

7 Claims. (Cl. 164—76)

This invention relates to a fabric cutting device of the rotary blade type.

An object of the invention is to provide a fabric cutting device of the kind stated wherein the bearings for the rotary blade will be of an improved balanced character constructed and arranged in such a manner that long continued operation will not result in appreciable wear or in any injurious play between the parts of the bearings.

Another object of the invention is to furnish the bearings of the device with an improved dust proof construction which will effectually prevent them from injury by reason of the entrance of any matter that would cause wear.

Still another object of the invention is to provide improved means for detachably mounting the cutting blade, said blade being conveniently removable in order that a larger or smaller cutter 20 may be substituted therefor, or in order that it may be replaced by a new and sharper blade of the same size when that is necessary.

Yet another object is to provide a means to prevent the material being cut from being drawn 25 into the running parts of the knife or cutter.

Other objects, advantages and features of the invention may hereinafter appear.

Referring to the accompanying drawing which illustrates what is at present deemed to be a preferred embodiment of the invention,

Fig. 1 is a vertical mid-section of the main parts of the device the upper portion thereof being shown in elevation. In this view the plane of section is indicated by the line 1—1 of Fig. 2.

Fig. 2 is a side elevation thereof looking at the right side of the structure shown in Fig. 1.

Fig. 3 is an end elevation of the complete device showing the same on a smaller scale than in Figs. 1 and 2.

Fig. 4 is a side elevation of a portion of the device showing the same on the same scale as Fig. 3 and looking in the opposite direction from the showing of Fig. 2.

Referring in detail to the drawing, the operative parts of the device are mounted upon a base member 5 by means of a standard 6 having a foot portion 7. Said foot portion is seated in a recess provided therefor in the upper face of the base member 5 in order that the upper surface of said foot portion may be made flush with the upper surface of the base member 5. Said foot portion may be secured in place by any suitable means as by the cap screws 8.

The body portion 9 of the standard 6 is expanded in an edgewise manner and is of a con-

cavo-convex character in order to receive, on its concave side, means for rotatably mounting the circular cutter blade 10. The mouth or open side of the concavo-convex member 9 is surrounded by an internally screw threaded flange 60 or thickened portion 11 which in turn is furnished with an annular internal shoulder 12. An externally threaded retaining cap 14 is screwed into the portion 11, the inner face of said cap abutting against said annular shoulder 12. Said retaining cap 14 is provided with an outwardly directed circular central extension 15 which aids in housing the bearings which will presently be described.

Opposite to the circular extension 15 of the 70 internal cap 14 there is provided in the standard body 9 a circular recess 16 which is provided with a peripheral stepped portion 17 thus affording a seat for the outer ball bearing ring 18, there being an outer annular shoulder 19 which 75 aids in holding this part of the bearing in place. The companion ring 21 of the two-part balanced ball bearing is mounted in spaced axial relation to the ball bearing ring 18, said ring 21 being fitted within the seat provided by the cap extension or rise 15. With the outer bearing rings 18 and 21 respectively cooperate the inner bearing rings 18a and 21a, these inner rings being also in spaced relation to each other. Between said inner rings is fitted a bevel gear wheel 22 80 or pinion 23 carried by the motor shaft 24.

The inner bearing rings 18a and 21a are secured to the rotatable member 25 which, by preference and as shown, consists of an internally 90 threaded sleeve. The inner bearing rings 18a and 21a, together with the driven gear 22, are mounted upon member 25 by means of a press fit, so that these four parts rotate in unison. The rise 15 of the cap member 14 is provided with 95 a central aperture sufficiently large to keep this part of the cap out of engagement with the rotatable member 25.

The rotatable assembly which carries the circular cutter 10 includes a circular dust guard 100 plate 26 which has around its inner face an annular lip or guard element 27 that cooperates with a recess 28 of a circular character provided therefor in that side of the standard body 9. A similar effect would be secured by forming the 105 lip upon the support and making a groove to cooperate therewith in the rotatable blade 10. Said guard plate 26 is provided with a circular central rise or extension 29 which is externally screw threaded to have screwed there onto the 110

tapered clamping nut 31, the inner side of said nut abutting against the outer side of the circular knife 10 and clamping it against the guard plate 26. The rotatable assembly is also provided with a clamping screw 30 which consists of a shank 32 which by means of the screw's head 33 is firmly screwed into the threaded bore of the rotatable member 25, the head of said screw abutting against the outer face of the rise 10 29 of the guard plate 26.

In order to insure that the rotatable member 25 and guard plate 26 remain in fixed relation to each other, a key 34 is provided between said rotatable member and guard plate. The central portion of the extension or rise 29 of the guard plate 26 is provided with an internal central circular recess 34a around the aperture which is necessarily provided through this part of the cap to receive the retaining screw 30, said screw 30 having, beneath its head, an annular shoulder 30s which is fitted into this aperture. One side of the key 34 engages a recess provided therefor in the end of the rotatable member 25 and the other side of said key engages a recess 20 in the rise 15. A key 35 is also provided to lock together the cutter 10 and guard plate 26, said key consisting of a projection preferably integral with the guard plate 26. The key 34 may be a separate piece, it being held in its operative position by the head 33 of the screw 30.

The device is designed to be driven from any conveniently accessible electric light fixture which furnishes current to the motor 41, which is provided with a control switch 42. The device is also furnished with an operating handle 43 whereby it may be bodily lifted. Said handle also being used to move the device across a plane supporting surface such as a desk or table. The supporting rollers 44 adapt it for being moved in this manner.

The base plate 5 is desirably provided at its front end with an inclined nose or bevelled part 45 to aid in directing the cloth into the angle between said blade and the front side of the cutter 10. The back side of the base 5 may also be provided with a bevelled portion 46. The base 5 is shown having a cut-away portion 47 thus providing an unobstructed space for the lower side of the cutter 10.

The inner cap plate 14 is preferably provided with recesses 14x in order that a spanner wrench may be applied to it to screw it firmly into place. The tapered nut 31 may likewise be provided with recesses 31x to receive a spanner wrench.

In the manufacturing of the device the driven gear wheel 22, sleeve 25 and inner bearing rings 18a and 21a are assembled at the shop, being secured together by means of a press fit. The dust guard plate 14 is then manually pushed over the bearing ring 21 which is seated therein with a snug fit. After said guard plate has been united to the parts being assembled it is screwed into place within the internally screw threaded portion 12 of the support, the outer bearing ring 18 of the left hand bearing race as viewed in Fig. 1 being seated within the recess provided therefor, as this is done. The dust guard plate 26 may now be slipped over the rise 15 of the plate 14 with relation to which it has a running fit, thereupon the cutter blade 10 is fitted over the rise 29 of the guard plate and then the tapered nut 31 is screwed on to the rise 29 to clamp the cutter blade 10 in place. The assembling is completed by screwing the clamping screw 30 into the sleeve 25.

I claim:

1. In a cloth cutter, a support, a two-part ball

bearing, the two parts of said bearing being in spaced axial relation to each other, said ball bearing being mounted upon said support, a rotatable member supported by the two parts of said bearing and bridging the space between them, a driven wheel mounted between the parts of said bearing and in fixed relation to said member in order that it may rotate the latter, means to rotate said wheel, a circular cutter fixed to said rotatable member and a dust guard plate in fixed relation to said cutter and located between it and said support, said support having an annular recess and said guard plate having an annular lip extending into said recess.

2. In a cloth cutter, a support, a bearing mounted upon said support, a rotatable member extending through said bearing, said bearing consisting of inner and outer rings separated by antifriction elements and said rotatable member being fixed to an inner ring of said bearing, a wheel fixed to said rotatable member, means to rotate said wheel, a retaining cap for said bearing, said cap having a central rise which aids in housing said bearing and with which an external ring of the bearing is associated in a fixed relation, a rotatable guard plate fixed to said rotatable member exteriorly of said cap, said guard plate having a circular guard element which cooperates with a circular seat formed therefor in the supporting means, and a circular cutter blade mounted externally and axially upon said guard plate to rotate therewith in fixed relation thereto.

3. In a cloth cutter, an upstanding support having a concavity in one side thereof, a bearing mounted upon said support in said concavity, an internal cap having a circular central rise, said cap being secured to said support with the rise thereof directed away from said concavity to form a housing for said bearing, a rotatable member supported by said bearing, a circular guard plate secured to said rotatable member, said guard plate having a central rise within which the rise of the internal cap is nested, and a cutter blade secured to said guard plate externally thereof to rotate therewith.

4. The subject matter of claim 3 and, said guard plate extending radially beyond the periphery of said internal cap, there being an annular lip and an annular groove connection between the peripheral portion of said guard plate and said upstanding support to keep dust out of the bearings.

5. In a cloth cutter, an internally threaded sleeve, a gear wheel fitted over said sleeve in spaced relation to each end thereof and secured to said sleeve by means of a press fit, a ball bearing member secured to said sleeve by a press fit at each side of said gear wheel, an upstanding support having a recessed or concave face to aid in housing said bearings together with said sleeve, said support having an annular recess to seat one of said bearings, a retaining plate having a central circular rise within which the other of said bearings is seated, said retaining plate being secured to said support and said retaining plate having a central aperture through which an end portion of said sleeve projects, a circular cutter secured to the projecting portion of said sleeve, and means to rotate the aforementioned wheel to operate said cutter.

6. In a cloth cutter, an internally threaded sleeve, a gear wheel fitted over said sleeve in spaced relation to each end thereof and secured to said sleeve by means of a press fit, a ball bearing member secured to said sleeve by a press

fit at each side of said gear wheel, an upstanding support having a recessed or concave face to aid in housing said bearings together with said sleeve, said support having an annular recess to seat one of said bearings, a retaining plate having a central circular rise within which the other of said bearings is seated, said retaining plate being secured to said support and said retaining plate having a central aperture through which an end portion of said sleeve projects, a dust guard plate secured to the projecting portion of said sleeve, said plate having a central circular rise within which the central rise of said retaining plate is nested, a circular cutter, 10 said cutter being mounted upon said guard plate

and having a central aperture through which the rise of said guard plate projects, and a clamping nut screwed on to the rise of said guard plate to clamp said cutter against the outer face thereof.

7. In a cloth cutter, a support, a rotatable member, a bearing whereby said member is mounted upon said support, a driven wheel fixed to said rotatable member, a circular cutter also fixed to said rotatable member, and a dust guard plate in fixed relation to said cutter and located between it and said support, said support having an annular recess and said guard plate having an annular lip extending into said recess.
